(57) **CLAIM**

The ornamental design for an independent suspension arm for a vehicle having a diagonal reinforcing member, as shown and described.

DESCRIPTION

FIG. 1 is a front view of an independent suspension arm for a vehicle having a diagonal reinforcing member having the inventive design;

FIG. 2 is a rear view of the independent suspension arm for a vehicle having a diagonal reinforcing member shown in FIG. 1;

FIG. 3 is a top front right side perspective view of the independent suspension arm for a vehicle having a diagonal reinforcing member shown in FIG. 1;

FIG. 4 is a right side view of the independent suspension arm for a vehicle having a diagonal reinforcing member shown in FIG. 1;

FIG. 5 is a top view of the independent suspension arm for a vehicle having a diagonal reinforcing member shown in FIG. 1;

FIG. 6 is a bottom view of the independent suspension arm for a vehicle having a diagonal reinforcing member shown in FIG. 1;

FIG. 7 is a top front left side view of the independent suspension arm for a vehicle having a diagonal reinforcing member shown in FIG. 1;

FIG. 8 is a bottom front right side perspective view of the independent suspension arm for a vehicle having a diagonal reinforcing member shown in FIG. 1; and,

FIG. 9 is a bottom rear perspective view of the independent suspension arm for a vehicle having a diagonal reinforcing member shown in FIG. 1.
